MARSHALL MONTGOMERY AND HENRY M. STEWART, OF PHILADELPHIA, PENNSYLVANIA, ASSIGNORS TO MONTGOMERY BROTHERS, INCORPORATED, A CORPORATION OF PENNSYLVANIA.

PACKING FOR STEAM AND HYDRAULIC USE.

1,117,688.

Specification of Letters Patent.

Patented Nov. 17, 1914.

Application filed June 13, 1914. Serial No. 844,865.

To all whom it may concern:

Be it known that we, MARSHALL MONTGOMERY and HENRY M. STEWART, citizens of the United States, and residents of Philadelphia, county of Philadelphia, and State of Pennsylvania, have invented an Improvement in Packing for Steam and Hydraulic Use, of which the following is a specification.

10 The object of our invention is to provide an effective construction of steam and water packing suitable for packing piston rods, plungers, etc., the packing being easily applied in use and adjustable under normal 15 compression to adapt itself to the shape of the chamber which it is to occupy.

Our object is further, to so combine the wearing sections of the packing with an intermediate connecting, yielding portion 20 that the several parts may be normally held in relative position without the necessity of braided or other coverings as heretofore in common use.

Our invention consists of a packing of 25 general rectangular or square cross section and comprising two wearing strips of vulcanized fibrous material, each of substantial triangular cross section, said sections united on their diagonal opposing surfaces 30 by an elastic section extending diagonally across the packing, all of said sections being vulcanized into union to form one unitary body.

Our invention also comprehends other 35 features of construction which, together with the improvements above specified, will be better understood by reference to the drawings, in which:—

Figure 1 is a cross sectional view of a 40 packing embodying our invention; Fig. 2 is a cross section showing the juxtaposed relation of two portions, rings or coils of our improved packing in use; and Figs. 3 to 6 are cross sectional views of modifications of our invention.

Referring to Figs. 1 and 2, the packing is substantially square or rectangular in cross section and comprises the triangular 50 wearing portions or sections 2 and 3 having oblique or diagonal opposing surfaces, which are united by the interposed diagonal section 4 of rubber. The sections 2 and 3 are each formed of superposed layers of rubberized fabric pressed together and vul-

canized into an integral strip. These strips 55 or sections 2 and 3 are connected by the oblique rubber sheet or layer 4 arranged between the sections 2 and 3, which is vulcanized into permanent adherence to said sections. This yielding rubber connection 60 4 is made on a diagonal to the sides of the packing as a whole, and is of sufficient thickness to give capacity to the two sections 2 and 3 to be relatively movable under compression. This packing when compressed in a vertical direction, Fig. 1, will spread laterally to widen itself commensurately with its compression. The packing may be cut into rings or employed in spiral form and placed in the packing receiving 70 chamber, and when subjected to compression, by tightening the usual gland upon it, the section 2 will be forced downward and laterally, the latter movement being the resultant of the oblique opposing faces of 75 the sections 2 and 3 when relatively shifted one over the other. In this way, the packing widens within the annular packing chamber and puts pressure upon the piston rod or plunger to make a tight joint. In 80 Fig. 2, we have shown two juxtaposed sections of the packing, of which there may be any number desired, according to requirements. It will be noted in this figure, that where the rubber terminates above the 85 fiber at 5, the fiber or textile surface 5^a of the next section presses directly upon the rubber, and on the compression, approaches the section 2 so as to reduce the thickness of the interposed rubber exposed at 5, as 90 is desirable. In this way, the packing in use will present a large amount of textile fiber and very little rubber to the piston rod or plunger.

In the construction shown in Fig. 3, we 95 have the outer top and bottom layers of the sections 2 and 3 extended over the diagonal rubber section 4, so that each packing ring will have within itself the fiber body 6 over the rubber at 5 to compress it and 100 minimize the rubber surface exposed to the piston rod.

In Fig. 4, we have shown a modification where greater elasticity is required and in this case the rubberized fibrous or cloth 105 layers 6 of Fig. 3 are substituted by rubber layers 7 at top and bottom; but being thinner than the vertical thickness of the

diagonal rubber section 4, these layers do not interfere with the function of the rubber section 4 in its attached relation to the wearing and packing sections 2 and 3. This 5 use of the rubber layers 7 would be better suited to machines of low temperature, but may be employed for all general uses, if so desired.

In the construction shown in Fig. 5, we 10 have formed the sections 2^a and 3^a in a somewhat different manner, but the packing as a whole is substantially of the same general construction shown in the other figures. In this case, the portions of triangular cross section, 2^a and 3^a, are formed of a rubberized asbestos sheet rolled up and compressed into triangular cross section and vulcanized, and these in turn vulcanized to the interposed diagonal section 4 of rubber. We 15 have also shown in this Fig. 5, by way of example, the use of an envelop of braided cotton 8; but as all of the sections in these packings are vulcanized into one unitary structure, such envelop will not ordinarily be required. Such an envelop may be used 20 in any of the forms of our invention, or omitted, as preferred. If used, the envelop, braided or otherwise suitably formed, may be impregnated with plumbago, tallow or 25 other lubricant, separately or in association with other substances.

In Fig. 6, we have shown the construction substantially shown in Fig. 1, but in this case the rubberized fabric sections 2 and 3 30 may be true triangles and the rubber section 4 extend equally on its ends both upon the top and sides of the complete unitary structure.

We have shown the preferred forms of 40 our packing and which we have found satisfactory in practice, by way of illustration of the nature of our invention, but we do not restrict ourselves thereto, as the details may be modified in various ways without 45 departing from the spirit of the invention.

Having now described our invention, what we claim as new and desire to secure by Letters Patent, is:—

1. Packing for steam and hydraulic use,

comprising two parallel strips of rubberized 50 fibrous material each composed of superposed fabric layers of different widths and substantially triangular in cross section and presenting opposed diagonal surfaces, and a connecting diagonal strip of rubber interposed between the first mentioned strips of triangular cross section, the three strips all vulcanized into a unitary structure the interposed rubber strips providing a yielding 55 connection between the two triangular strips 60 and permitting them to shift under compression to widen the width of the packing while maintaining the unitary character of the structure.

2. Packing for steam and hydraulic use, 65 comprising two parallel strips of rubberized fibrous material each substantially triangular in cross section and presenting opposed diagonal surfaces, a connecting diagonal strip of rubber interposed between the first 70 mentioned strips of triangular cross section, and outer thin layers of rubber upon the opposite ends of the two triangular strips said rubber layers uniting respectively with the ends of the diagonal rubber layer, the three 75 strips all vulcanized into a unitary structure.

3. Packing for steam and hydraulic use, 80 comprising two parallel strips of triangular cross section formed of dense but slightly yielding material and presenting diagonal opposed surfaces, and an interposed elastic layer vulcanized to each of said diagonal surfaces for uniting the parallel strips into a unitary structure and so as to provide a very yielding union whereby the layers may be shifted relatively to each other 85 under compression to widen the packing while maintaining their permanent union with the elastic layer. 90

In testimony of which invention, we hereunto set our hands.

MARSHALL MONTGOMERY.
HENRY M. STEWART.
